(57) **CLAIM**

The ornamental design for vehicle-wheel front face, as shown and described.

DESCRIPTION

FIG. 1 is a perspective view of a vehicle-wheel front face according to my new design;

FIG. 2 is a front elevational view thereof; and,

FIG. 3 is a side elevation of FIG. 2.

The portion of the wheel depicted in broken lines is for illustrative purposes only, and forms no part of the claimed design.
